UNITED STATES PATENT OFFICE

170,506

TORQUE WRENCH

Frank W. Livermont, Duarte, Calif.

Application January 19, 1953, Serial No. 23,182

Term of patent 14 years

(Cl. D54—16)

To all whom it may concern:

Be it known that I, Frank W. Livermont, a citizen of the United States of America, residing at Duarte, in the county of Los Angeles, State of California, have invented a new, original, and ornamental Design for a Torque Wrench, of which the following is a specification, reference being had to the accompanying drawings forming a part thereof:

Figure 1 is a perspective view of a torque wrench showing my new design.

Figure 2 is a bottom plan view.

Figure 3 is a side elevation.

Figure 4 is a top plan view.

Figure 5 is an end view.

The dominant features of my design are shown in solid lines.

I claim:

The ornamental design for a torque wrench, as shown and described.

FRANK W. LIVERMONT.
